ATTORNEYS

UNITED STATES PATENT OFFICE.

WILLIAM L. C. KOCH, OF SCRANTON, PENNSYLVANIA.

ROWLOCK.

Application filed April 18, 1922. Serial No. 554,960.

To all whom it may concern:

Be it known that I, WILLIAM L. C. KOCH, a citizen of the United States, residing at Scranton, in the county of Lackawanna and State of Pennsylvania, have invented new and useful Improvements in Rowlocks, of which the following is a specification.

This invention relates to a universal joint rowlock, which includes a forked body adapted to turn on a vertical axis, and trunnions attached to and projecting from opposite sides of the shaft of an oar, and adapted to turn on a horizontal axis in bearings in the arms of the forked body.

One object of the invention is to provide improved means whereby the trunnions may be conveniently and securely attached to an oar shaft, and whereby, during the attaching operation, the operator is enabled to so adjust the blade as to impart a suitable feathering angle thereto.

Another object is to enable the trunnions and the oar to which they are attached, to be quickly and conveniently installed in, and removed from the forked body, and securely connected with the body against liability of accidental separation therefrom.

Of the accompanying drawings forming a part of this specification,—

Figure 1 is a perspective view of a rowlock embodying the invention.

Figure 2 is a sectional view of the same.

Figure 3 is a sectional view showing a modification.

The same reference characters indicate the same parts in all of the figures.

In the drawings, 12 represents the shank, and 13 and 14 the arms of a forked metal body, having the general form of an ordinary metal rowlock. The shank is adapted to turn as usual, on a vertical axis in a socket in the gunwale of a boat. 15, 15 represent trunnions rigidly secured to the shaft of an oar at a suitable point between the handle portion and the outer end of the blade. The preferred means for securing the trunnions to the oar shaft is embodied in a cut band 17, adapted to embrace an oar shaft, and provided with holes 16, for fastening members, such as screws attaching the band to the shaft. The trunnions are adapted to turn in bearings in the arms 13 and 14, arranged to support the trunnions horizontally, so that an oar to which the trunnions are attached is adapted to swing on a horizontal axis formed by the trun-

nions, and on a vertical axis formed by the shank 12. The continuity of the band 17 is interrupted by a slot 18, which is arranged at one side of the vertical axis, as shown by Figure 2, its position with relation to the center of the space surrounded by the band being such, that when an oar shaft is inserted in the band, and turned until the plane of the oar blade 19 coincides with the slot, as indicated by dotted lines in Figure 2, the blade is at the proper angle for feathering. The slot 18, therefore, serves as a guide or gage, whereby an operator is enabled to attach the band to the oar shaft in position to cause the oar blade to assume a feathering angle when the trunnions are installed in their bearings.

To permit the quick application and removal of the trunnions to and from their bearings, I provide the arm 13 with a substantially circular orifice 21, which is enlarged at its inner end, and constitutes one of the bearings, the outer end of said orifice being formed to permit a trunnion to turn therein without moving sidewise. I also provide the arm 14 with a vertically elongated slot 22, the lower end of which constitutes the bearing for the other trunnion, the slot permitting the trunnion journaled therein to swing upward, out of engagement with the arm 14, as shown by dotted lines in Figure 3. The other trunnion is permitted to swing upward in the orifice 21, by the enlargement of the inner end of said orifice.

The slotted arm 14 is provided with a detent, adapted to prevent the removal of the trunnions from the arms and displaceable to permit such removal. As here shown, the detent is embodied in a resilient shank 24, one end of which is attached at 25 to the arm 14, and a head 26, carried by the free end of the shank, and normally held thereby in position to confine the trunnion in said slot in its operative position. The detent may be swung outward to withdraw it from its holding-down position. The lower side of the detent head 26 is preferably parallel with the trunnion, so that it is adapted to positively hold down the latter. The back of the head is preferably so curved or inclined, that a trunnion swung downward from the raised position shown by dotted lines in Figure 3, will first outwardly displace the head and then allow it to swing inward.

The trunnions 15 may be attached to an oar shaft by means other than the band 17, and may form the ends of a rod or pin 15^a, which is driven through and tightly secured in an oar shaft 26, as shown by Figure 2.

I claim:

1. A rowlock comprising a body including a shank adapted to turn in a gunwale socket, and fork arms projecting upward from the shank, and each provided with a bearing, and a band adapted to embrace and be secured to the shaft of an oar, and provided with trunnions adapted to turn in said bearings, the continuity of said band being interrupted by a slot, permitting the compression of the band upon the oar shaft, and arranged at one side of the vertical axis of the body to provide means whereby, during the operation of attaching the blade to an oar shaft, the operator is enabled to so adjust the oar blade as to impart a suitable feathering inclination thereto.
2. A rowlock comprising a body including a shank adapted to turn in a gunwale socket, and fork arms projecting upward from the shank, one of said arms having a vertically elongated slot, the lower end of which constitutes a trunnion bearing, the other arm being provided with a substantially circular orifice constituting another trunnion bearing; a pair of trunnions

adapted to be secured to the shaft of an oar, and to turn on said bearings, the said slot and the circular bearing being formed to permit the separation of the trunnions from the fork arms, and a displaceable detent engaged with the slotted arm, and adapted to prevent the removal of the trunnions from the fork arms.

3. A rowlock substantially as specified by claim 2, said detent being embodied in a resilient shank fixed at one end to the slotted arm, and a head carried by the free end of said shank, and normally held by the latter in position to confine the slot-engaging trunnion in its operative position, at the lower end of said slot.

4. A rowlock substantially as specified by claim 2, said detent being embodied in a resilient shank fixed at one end to the slotted arm, and a head carried by the free end of said shank, and normally held by the latter in position to confine the slot-engaging trunnion in its operative position, at the lower end of said slot, said head having a lower face formed to positively confine the slot-engaging trunnion in its operative position, and an upper face formed to be displaced by said trunnion during the operation of engaging the trunnion with the fork arms.

In testimony whereof I have affixed my signature.

WILLIAM L. C. KOCH.
